(57) **CLAIM**

The ornamental design for a tire, as shown and described.

DESCRIPTION

FIG. 1 is a front view of the tire showing my new invention; FIG. 2 is a partial front view thereof;

FIG. 3 is a left side view thereof;

FIG. 4 is a right side view thereof; and,

FIG. 5 is a perspective view thereof.

The broken lines depict the location and borders of the enlarged fragmentary view of FIG. 2 and form no part of the claim.
